His Attorney

UNITED STATES PATENT OFFICE.

ERNST F. W. ALEXANDERSON, OF SCHENECTADY, NEW YORK, ASSIGNOR TO GENERAL ELECTRIC COMPANY, A CORPORATION OF NEW YORK.

RADIO RECEIVING SYSTEM.

Application filed June 24, 1921. Serial No. 460,220.

To all whom it may concern:

Be it known that I, ERNST F. W. ALEXANDERSON, a citizen of the United States, residing at Schenectady, in the county of 5 Schenectady, State of New York, have invented certain new and useful Improvements in Radio Receiving Systems, of which the following is a specification.

My present invention relates to radio receiving systems, and more particularly to 10 means for preventing interference in such systems with the reception of desired signals.

The object of my invention is to provide 15 in a radio receiving system a means for preventing interference with the reception of desired signals from a near-by transmitting station having a different wave length.

In carrying my invention into effect I 20 provide in connection with a receiving antenna means for impressing upon the receiving circuit two equal and opposing potentials produced in the antenna by the interfering wave. This means is so arranged that 25 it will also impress upon the receiving circuit two potentials produced by the desired signaling waves, but these two potentials will be of different magnitude and of the same phase or will have such phase relation 30 to each other that they will add in the receiving circuit and will not neutralize one another.

The novel features which I believe to be 35 characteristic of my invention are set forth in the appended claims. The invention itself, however, both as to its organization and method of operation will best be understood by reference to the following description taken in connection with the accompanying 40 drawing in which I have indicated diagrammatically one way in which my invention may be carried into effect.

As indicated in the drawing, I provide in 45 connection with the receiving antenna 1 in addition to the ordinary antenna tuning coil 2, two special tuned circuits, one being a multiple tuned circuit made up of inductance 3 and capacity 4 and the other being a series tuned circuit made up of inductance 5 and capacity 6. These two circuits are 50 adjusted so that they are both in resonance for the signal which it is desired to suppress. The inductances and capacities of these two circuits are selected so that the multiple

tuned resistance of the first circuit is substantially equal to the series tuned resistance of the second circuit. Each of the circuits has the character of a non-inductive resistance at the frequency to which they are tuned, hence the voltage drops between 55 the terminals of each of these two circuits are equal and in phase. The voltage drop across the first tuned circuit is impressed by means of the coupling transformer 7 upon a receiving circuit and the voltage drop across 60 the second tuned circuit is also impressed by means of the coupling transformer 8 upon the receiving circuit which is associated with a detector 9 of the audion type. The couplings 7 and 8 are so arranged that 65 the potentials of a frequency equal to that of the waves to be suppressed oppose each other in the receiving circuit and their effect is thus neutralized. Thus no signal will be received or detected of the frequency for 70 which the two circuits are tuned. If, however, the frequency of the signal to be received is only slightly greater than the frequency for which these two circuits are 75 tuned the multiple tuned circuit assumes the 80 character of a capacity and the series tuned circuit assumes the character of an inductance. Thus the phase of the voltage drops produced by the desired signal across the 85 two circuits is shifted in opposite directions. By properly proportioning the circuits the voltage drops produced across these circuits by the desired signal may be made to be 90 substantially opposite in phase so that they will add in the receiving circuit. The magnitude of the voltage drop across the multiple tuned circuit will also be less than the 95 voltage drop across the series tuned circuit.

It will thus be apparent that the signal which has a frequency only slightly different from that of the interfering wave may be received with practically full intensity at the same time that the interfering wave is neutralized.

What I claim as new and desire to secure 100 by Letters Patent of the United States, is:—

1. Means for eliminating disturbing effects in a radio receiving system comprising a receiving antenna, a multiple tuned circuit connected to said antenna which is resonant to the frequency of the disturbing effect to be eliminated, a series tuned circuit connected to said antenna which is also 105

resonant to the frequency of the disturbing effect to be eliminated, a receiving circuit and means for impressing upon the receiving circuit electromotive forces derived from 5 both of said resonant circuits.

2. Means for eliminating disturbing effects in a radio receiving system comprising a receiving antenna, a multiple tuned circuit connected to said antenna which is resonant 10 to the frequency of the disturbing effect to be eliminated, a series tuned circuit connected to said antenna which is also resonant to the frequency of the disturbing effect to be eliminated, the multiple tuned resistance of the first circuit being substantially 15 equal to the series tuned resistance of the second, a receiving circuit and means for impressing upon the receiving circuit elec-

tromotive forces derived from both of said resonant circuits.

3. A receiving system for radio signals comprising a receiving antenna and means for deriving from said antenna and impressing upon a receiving circuit two radio frequency electromotive forces of equal intensity and opposite sign produced by undesired waves of definite frequency in said antenna, said means being arranged to impress upon the receiving circuit two electromotive forces produced in said antenna by desired signaling currents and which will add in the receiving circuit.

In witness whereof, I have hereunto set my hand this 23rd day of June, 1921.

ERNST F. W. ALEXANDERSON.
